Des. 194,451
Patented Jan. 29, 1963

194,451

DOOR STOP

John R. Morgan, Chicago, Ill., assignor to Amerock Corporation, Rockford, Ill., a corporation of Illinois

Filed Nov. 2, 1961, Ser. No. 67,350

Term of patent 14 years

(Cl. D10—7)

FIG. 2 is a front elevational view of the door stop.

FIG. 3 is a top elevational view of the door stop.

FIG. 4 is a side elevational view of the door stop.

I claim:

The ornamental design for a door stop, substantially as shown.
